(57) **CLAIM**

The ornamental design for an impact shock bumper, as shown and described.

DESCRIPTION

FIG. 1 is a perspective view of an impact shock bumper showing our new design;

FIG. 2 is a top plan view of the configuration as shown in FIG. 1;

FIG. 3 is a bottom plan view of the configuration as shown in FIG. 1;

FIG. 4 is a right side elevational view of the configuration as shown in FIG. 1;

FIG. 5 is a left side elevational view of the configuration as shown in FIG. 1;

FIG. 6 is a front view of the configuration as shown in FIG. 1; and,

FIG. 7 is a rear view of the configuration as shown in FIG. 1.

The broken line area as showing portions of the impact shock bumper that form no part of the claimed design.

1 Claim, 7 Drawing Sheets(56)
